C. A. KJELLIN

CLOTHESLINE HOLDER

Filed June 1, 1927

Patented Feb. 5, 1929.

1,700,897

UNITED STATES PATENT OFFICE.

CHARLES A. KJELLIN, OF BROOKLYN, NEW YORK.

CLOTHESLINE HOLDER.

Application filed June 1, 1927. Serial No. 195,805.

This invention relates to clothes line holders and in particular to one that alleviates the necessity of the housewife leaning out of the window in order to place clothes upon a clothes line.

A particular object of the invention is to provide a simplified device which may be swung into and out of the window, which will carry the clothes line into the room so that the clothes may be hung thereon without the necessity of reaching out of the window to place the same upon the line.

A still further object of the invention is to provide a clothes line holding device which will be adjustable so that it can be placed in position upon a window of any width and so arranged that it can be swung to position exterior of the window.

A still further object of the invention is to provide a device of this character embodying a line holding hook which will compensate for the distance the line holding member is swung so that slack in the line will be taken up and the line prevented from sagging.

To enable others skilled in the art to fully comprehend the underlying features of my invention that they may embody the same in the various modifications in structure and relation contemplated, a drawing depicting a preferred form has been annexed as a part of this disclosure and in such drawings, similar reference characters denote corresponding parts throughout all the views, of which,

Figure 1 is a view in side elevation, the section being taken through a window to show the position of my improved line holding device in connection therewith.

Figure 2 is an enlarged view partly in section showing the device as it would appear when swung into the room and in position for use, the sectional parts thereof being arranged to show the construction of the device.

Figure 3 is a view in perspective showing how the device would appear when swung exteriorly of the window to support the line in position to dry the clothes, and

Figure 4 is a sectional view taken on the line 4-4 of Figure 2 showing how my improved device is secured to the casing of the window.

Referring to the drawings in detail and in particular to Figure 1, 5 indicates the wall of the dwelling and 6 a floor therein, the window sill being indicated as at 7 and the sash frame indicated by the numeral 8. The sash frame, of course, holds the two sliding sash

elements 9 and when the lower element is raised, my improved line holding device is adapted to be swung into the room so that clothes may be secured on the line without the necessity of the housewife reaching through the window opening.

In Figure 2 it will be evident that the device is secured to one side of the window frame 8 and consists of a bracket 10 having the extended portions 11 and 12 which, through the medium of the screws or other fastening element 13, are secured in position against the window frame 8 and at one side of the window so that the clothes line holding device is positioned as shown in Figure 3. The bracket 10 is provided with the sleeve portions 14 through which is adapted to pass and have sliding fit therein, the short piece of pipe 15 which is prevented from moving upwardly through the sleeve 14 by means of the cap 16 which is threaded to its lower end, the upper end of the pipe 15 receiving the elbow 17 which imprisons between its end and the upper end of the bracket sleeve 14, the hook member 18. This hook member consists of a sleeve arranged to encompass the pipe 15 and has formed integral therewith, a holding hook.

It is quite evident, therefore, that the pipe member 15 has free swinging movement in the bracket sleeve 14 and consequently, the extended portion 19 which is made from a piece of pipe and is threaded into the end of the elbow 17 may be swung in and out of the window.

This piece of pipe 19 is adapted to receive the pulley carrying arm or extension 20 which has sliding movement through the cap 21 which is not only threaded to the end of the pipe 19 and forms a closure therefor but has passing therethrough the set screw 22 which is adapted to engage the extension 20 to retain the same in any adjusted position. The end of the extension or rod 20 is provided with a turned over portion 23 arranged to hold in position the pulley bracket 24 in which, in the usual manner, the pulley 25 is pivoted over which passes the clothes line 26, the other end thereof passing over the pulley 27 which is held on any suitable support such as the clothes line holding pole 28.

It is quite evident, therefore, that when the device has been drawn to the position shown in Figure 1 that clothes may be placed on the clothes line in that portion thereof which is disposed within the room and one side of

the line 29 may be passed over the hook 18 to keep it out of the way of the other portion of the line when the clothes are being secured thereto, and when the line has been 5 hung with clothes and the line is advanced so that the last article of clothing hung thereon is outside the window, the piece 19 is swung out so that it extends beyond the window as shown in Figure 3. When the device 10 is swung into the room, it is maintained in this position through the medium of a suitable pin 30 which passes through an opening in the sleeve portion 14 of the bracket 10 and through matching openings in the 15 pipe 15, the openings in the sleeve and in the pipe are diametrically opposite and consequently the pin 30 passing through the openings maintains the device in the position shown in Figure 2, when it is desired to hang 20 clothes on the line and in its outwardly swung position, as shown in Figure 3. The adjustment of extension piece 20 permits the device to be used in connection with windows of various width thereby permitting the pulley to 25 be drawn into the room a maximum distance.

When the line is advanced to carry the clothes beyond the window, the pin is removed and the device is swung about the bracket to the position shown in Figure 3 but 30 preparatory to doing this both sides of the clothes line are put into the hook 18 and when the device is swung outwardly of the window, the line is folded as illustrated in Figure 3 and thus slack therein is prevented 35 and taken up by reason of the fold in the line when the bracket is moved to its extended position outside the window. When it has been moved to this position, the pin 30 is reinserted and the device is held in its extended 40 position until it is desired to remove the clothes from the line.

It is evident, therefore, that I have provided a device which eliminates the necessity of the housewife reaching out of the window 45 and also takes up the weight of the line so

that the same may be more readily drawn into or out of the room and one which positions the line so that the clothes may be hung in the room with a minimum of effort and a consequently saving of time. 50

It is also evident that I have provided a device which takes up the slack in the line, which is made of few parts, which will not get out of order readily and which can be made up cheaply at a saving to the user. 55

While I have illustrated and described my invention with some degree of particularity, I realize that in practice various alterations therein may be made. I therefore reserve the right and privilege of changing the form of 60 the details of construction or otherwise altering the arrangement of the correlated parts without departing from the spirit of the invention or the scope of the appended claim. 65

Having thus described my invention what I claim as new and desire to secure by United States Letters Patent is:—

A clothes line holder comprising a bracket, a sleeve like housing thereon having oppositely disposed openings, a tubular member revolvable therein and having openings to match with those of the housing, a cap for the lower end of the tubular member, an elbow secured to the upper end thereof, a 70 sleeve carried by the tubular member disposed between the elbow and the upper end of the housing and provided with a clothes line holding hook, a pipe secured to the elbow, an extension arm slidable in said pipe 75 and having a hooked end, means for securing the arm in any adjusted position in the pipe, a clothes line pulley carried by the hooked end of said extension and a pin arranged to pass through the openings of the 80 housing and the tubular member for retaining the same in predetermined relative position. 85

In testimony whereof I affix my signature.

CHARLES A. KJELLIN. [L. S.]
